UNITED STATES PATENT OFFICE

157,234

BRACKET LIGHTING FIXTURE

Merton B. Briggs, Cincinnati, Ohio, assignor to
The Grote Manufacturing Company, Bellevue,
Ky., a corporation of Kentucky

Application October 8, 1948, Serial No. 149,036

Term of patent 3½ years

(Cl. D48—4)

To all whom it may concern:

Be it known that I, Merton B. Briggs, a citizen of the United States, residing at Cincinnati, in the county of Hamilton and State of Ohio, have invented a new, original, and ornamental Design for Bracket Lighting Fixture, of which the following is a specification, reference being had to the accompanying drawing, forming a part thereof.

Figure 1 is a side elevation of a bracket lighting fixture showing my new design.

Fig. 2 is a front elevation thereof.

Fig. 3 is a bottom view and

Fig. 4 is a front perspective view taken from a point above and at one side of the center of Fig. 2.

I claim:

The ornamental design for a bracket lighting fixture, as shown.

MERTON B. BRIGGS.
